RIDING VEHICLE

Laurie Jay Campbell, Robert T. Auer, Calvin S. Cook,
and Raymond J. Lohr, Erie, Pa., assignors to Louis
Marx & Co., Inc.

Filed Apr. 4, 1973, Ser. No. 347,735

Term of patent 14 years

Int. Cl. D21—01

U.S. Cl. D34—15 AJ

FIG. 3

FIG. 2

FIG. 1 is a front perspective view of an aircraft riding vehicle showing our new design;

FIG. 2 is a side elevational view thereof; and

FIG. 3 is a rear elevational view thereof.

We claim:

The ornamental design for a riding vehicle, as shown.
